CLAIM

The ornamental design for a spectacle display holder, as shown and described.

DESCRIPTION

FIG. 1 is an isometric view of the present invention, wherein the opening on the clip is positioned on a rearward side of the invention;

FIG. 2 is a front side-elevational view of the embodiment illustrated in FIG. 15.

FIG. 3 is a back side-elevational view of the embodiment illustrated in FIG. 15;

FIG. 4 is a second side-elevational view of the embodiment illustrated in FIG. 15;

FIG. 5 is a first side-elevational view of the embodiment illustrated in FIG. 15;

FIG. 6 is a top plan view of the embodiment illustrated in FIG. 15; and,

FIG. 7 is a bottom plan view of the embodiment illustrated in FIG. 15.
